UNITED STATES PATENT OFFICE

2,553,971

KNITTING CASE

Ruby Elizabeth Hunter, Boissevain, Manitoba,
Canada

Application September 27, 1948, Serial No. 51,365

1 Claim. (Cl. 223—107)

1

My invention relates to new and useful improvements in knitting cases, an object of the invention being to provide a device of the character herewithin described in which may be located the balls of wool, the knitting needles, and the partially finished work, thereby enabling same to be transported readily and easily without the possibility of the work becoming disengaged from the needles.

A further object of my invention is to provide a device of the character herewithin described which includes means for retaining a plurality of balls of wool distinct and separate from one another, each thread thereof having its own guiding aperture, thus preventing them from becoming intermingled.

A still further object of my invention is to provide a device of the character herewithin described which enables the partially completed knitting to be worked upon or replaced in the case immediately as desired.

Another object of my invention is to provide a device of the character herewithin described whereby the wool and partially finished knitting may be kept in a clean condition at all times.

A further object of my invention is to provide a device of the character herewithin described which is economical in manufacture, attractive in appearance, and otherwise well suited for the purpose for which it is designed.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which:

Figure 1 is a perspective view of my knitting case with the closure lid partially removed and the inner cover-panel raised to show the interior thereof.

In the art of knitting considerable difficulty has been experienced in the past in providing a self-contained receptacle which facilitates the transportation of the various items of equipment necessary. The majority of people usually desire to carry their knitting with them during a journey and find it extremely inconvenient when carried in the conventional knitting bag. It will be appreciated that present day transportation, necessitating one or more changes before arriving at the destination, does not lend itself to the occupation of knitting under these conditions. Consequently I have devised the case

hereinafter to be described the use of which permits the knitting to be worked upon or prepared for transportation immediately as desired.

Proceeding therefore to describe my invention in detail it will be seen upon reference to the accompanying drawing to comprise the relatively shallow open-topped rectangular case 1 manufactured from relatively rigid plastic material or the like and being provided with the carrying handle 2 situated upon one of the longitudinally extending sides 3. Spanning the sides 4 of the box coterminous with the upper edges thereof and the rear longitudinally extending side 5, is a relatively narrow panel 6 thus forming what I designate as my needle compartment. The medially situated dividing wall 7 extends between the sides 4 of the box and divides the box into the elongated rear or work compartment 8, alongside the front compartment 9. The transverse partitions 10 are situated vertically in parallel spaced relationship between the front side 3 of the box and the aforementioned wall 7 thus dividing the compartment 9 into four relatively small linearly arranged wool containing compartments 11. The partitions 10 are maintained in position between the vertically disposed pairs of cleats 12 which are rigidly attached to the front side 3 and the wall 7 by means of suitable adhesive or the like. Hingedly attached in the conventional manner to the upper edge of the wall 7 is the cover-panel 13 of rectangular configuration and having dimensions slightly smaller than the corresponding compartment 9. In this connection it is to be noted that the aforementioned wall 7 and the transverse partitions 10 are recessed slightly within the box in order to permit the aforementioned cover-panel 13 to lie flush with the upper edges thereof when in the closed position.

Strand passing apertures 14 are provided in the cover-panel 13, there being an aperture centrally disposed above each of the compartments 11. Serpentine slots 15 within the panel extend from the forward edge thereof to these apertures in order that the strand of wool may be introduced therein, the double curvature of the slot preventing undesirable displacement of the strand unless required. The tab 16 is provided centrally along the forward edge of the panel 13 and is receivable by the recess 17 situated in the upper edge of the front side 3 in order to assist in the opening and closing of the panel, it being appreciated that, when in the closed position, the panel 13 is flush with the uppermost edges

of the compartment 9 as hereinbefore described.

The main closure lid 18 comprises the top rectangular panel 19 having dimensions slightly smaller than the open part of the box and being provided with the two outstanding lifting tabs 20 in order to facilitate the removal and replacement thereof. The two vertical sides 21 extend downwardly from the ends of the top rectangular panel 19 and are provided with the vertical slots 22 centrally disposed in order to straddle the aforementioned dividing wall 7, thus permitting the lid to be lowered onto the box, the vertical ends 21 being designed to go within the ends 4 of the box when closed.

Having therefore described my invention in detail, its method of application will now be presented.

The balls of wool (not illustrated) are placed within the individual compartments 11 and the individual strands are passed through the serpentine slots 15 to the apertures 14 whereupon the cover-panel 13 may be closed. While knitting, the lid 18 should be removed whereupon the wool will feed through the apertures 14 as required. When it is desired to store the partially completed article, the article, together with the needles may be placed in the work compartment 8 whereupon the lid 18 may be replaced thus maintaining the equipment within the separate compartments. In this connection it should be noted that the vertically disposed apertures 23 are provided in the ends 4 subjacent the aforementioned panel 6 in order to receive knitting needles that may be longer than the dimensions of the box.

Since various modifications can be made in my invention as hereinabove described, and many apparently widely different embodiments of same made within the spirit and scope of the claim without departing from such spirit and

scope, it is intended that all matter contained in the accompanying specification shall be interpreted as illustrative only and not in a limiting sense.

5 What I claim as my invention is:

A multi-compartmented knitting case having a plurality of wool containing compartments therein in linear arrangement, an elongated work compartment alongside said linear arrangement of the wool compartments being separated therefrom by a medially situated dividing wall parallel with a pair of opposite side walls constituting part of the case, a cover-panel for said wool compartments, said panel being provided with a plurality of strand-passing apertures and serpentine passageways each extending from one edge of said panel to a different aperture for the purpose specified, the number of apertures and passageways corresponding to the number of compartments, and a closure lid for covering one side of said case having end walls for interior lapping relation with the corresponding walls of said case, said end walls being slotted to straddle said dividing wall and extending substantially to the base of said case to prevent accidental displacement of said lid when said case is being carried.
